UNITED STATES PATENT OFFICE

127,326

DESIGN FOR A ROUGE CONTAINER

William B. Petzold, Pittsfield, Mass., assignor to
General Electric Company, a corporation of
New York

Application March 21, 1941, Serial No. 99,759

Term of patent 14 years

To all whom it may concern:

Be it known that I, William B. Petzold, a citizen of the United States, residing at Pittsfield, in the county of Berkshire, Commonwealth of Massachusetts, have invented a new, original, and ornamental Design for a Rouge Container, of which the following is a specification, reference being had to the accompanying drawing, forming a part thereof.

In the drawing, Fig. 1 is a front perspective view of a rouge container, showing my new design. Fig. 2 is a plan view, and Fig. 3 is a view in elevation thereof.

I claim:

The ornamental design for a rouge container, as shown.

WILLIAM B. PETZOLD.
